Primary Examiner — Mark Goodwin(74) *Attorney, Agent, or Firm* — Dicke, Billig & Czaja, PLLC(57) **CLAIM**

The ornamental design for the double D-ring attachment point, as shown and described.

DESCRIPTION

FIG. 1 is a front perspective view of our double D-ring attachment point;

FIG. 2 is a rear perspective view thereof;

FIG. 3 is a front elevational view thereof;

FIG. 4 is a rear elevational view thereof;

FIG. 5 is a top plan view thereof, the bottom plan view being a mirror image thereof; and,

FIG. 6 is a left side elevational view thereof, the right side elevational view being a mirror image thereof.
